UNITED STATES PATENT OFFICE.

FREDERICK A. SHAW, OF DIGHTON, MASSACHUSETTS, ASSIGNOR TO AUGUSTUS A. GREEN, OF PROVIDENCE, RHODE ISLAND.

REPEAT DEVICE FOR PHONOGRAFS.

1,407,090.

Specification of Letters Patent. Patented Feb. 21, 1922.

Application filed February 16, 1921. Serial No. 445,543.

To all whom it may concern:

Be it known that I, FREDERICK A. SHAW, a citizen of the United States, residing at Dighton, in the county of Bristol and State

5 of Massachusetts, have invented new and useful Improvements in a Repeat Device for Phonographs, of which the following is a specification.

This invention relates to certain new and 10 useful improvements in a repeat device for phonographs, and it has for its primary object to provide a simple and efficient construction for expeditiously transferring the reproducing needle or stylus at the finish 15 or end of the sound groove to the beginning thereof without injury to the needle or to the record.

The invention consists, in part, of a shuttle or transferring member mounted eccentrically relative to the sound record, and adapted to swing in an arc also to the latter which arc traverses the sound grooves in an outward direction, the general operation being for the sound box to ride upon the 25 shuttle and offer sufficient resistance to the rotary movement thereof, along with the record, to cause the shuttle to swing on its pivotal mounting relative to the record, which action results in the shuttle and the 30 sound box, temporarily supported thereby, moving in an eccentric arc outwardly until the stylus is brought to its starting position whence the shuttle will move from under the same and permit it to drop gently onto 35 the record.

The invention further resides in an improved repeating device having a part surmounting the record and removable readily therefrom for a change of records.

40 The invention further resides in the features of construction and the arrangements and combinations of parts hereinafter described and claimed, reference being had to the accompanying drawings wherein:

45 Figure 1 is a perspective view of the playing table and tone arm of a phonograph, showing my invention embodied therein;

Figure 2 is a side elevation thereof showing the tone arm about to complete the 50 production of the record;

Figure 3 is a top plan view of the shuttle or return attachment;

Figure 4, is a diametrical section there- 55 through on line 4—4 of Figure 3;

Figure 5 is a perspective view of the stylus attachment; and

Figure 6 is a detailed section on line 6—6 of Figure 3 showing more clearly the latch for normally holding the shuttle in its receiving position.

In proceeding in accordance with the present invention, a disk-like, heavy base or body 1 is provided of a diameter substantially equivalent to the central area of a record bearing the title, etc., relating to the subject matter and producer of the article. To one side of the base or support is pivotally secured, as by pivot pin 2, the shuttle arm 3 which normally extends diametrically across the same and carries on its opposite end, slightly beyond the periphery of the base, the shuttle or sound-box-carrying member 4. The shuttle comprises an arcuate, channeled or U-sectioned member, the inner wall of which carries a spring 5 having its 75 terminal extending therethrough, as at 6, to obstruct the channel, while the outer wall is formed with a knife edge 7 at its forward end, the forward end of the channel bottom also tapering or formed with a gradual rise, 80 as depicted at 8. The shuttle is adjustably mounted on the free end of the arm 3 by means of the set screw 9 passing through the slot 10 in the inward extension from the shuttle, as is clearly shown in Figures 3 85 and 4.

The shuttle arm is retained in and urged to its normal position by means of a coiled spring 11 fixed at one end to the intermediate portion of the arm and at the opposite end 90 to the disk 12. The outer end portion of the arm carries a double-beveled keeper 13 for engagement by the spring latch 14, secured to the base 1, said latch being designed to frictionally hold the arm in its normal or 95 inoperative position.

The cooperating part carried by the tone arm or sound box, consists of a ring support 15 fastened to the inner side or back of the sound box, as by screws 16, the lower 100 edge of the ring having a downwardly deflected leg 17 which terminates in a felt-covered foot 18, said leg, intermediate its length being also provided with a pair of ears 19 between which is pivoted a lever 20 so mounted or weighted as to tend to swing inwardly at its lower end against the leg. A pin 21 depends from the lever but terminates short of the plane of the foot 18. The function of the latter is to prevent 110 the pin from contacting with the record in the event the sound box is turned over with-

out the stylus having first been inserted, in which case the felted foot will cushion the contact between the sound box and the record.

5 In operation, with the stylus working inwardly from the outer diameter of the record disk, the pin 21 will also be carried inwardly. As the latter approaches the path of movement of the shuttle and moves into said path, 10 the knife edge 7 will deflect the pin 21 inwardly on its pivotal mounting 19 so as to ride up the channel of the shuttle during which the shoulder 22 rides over the outer wall of the channel until arrested by the pin 15 coming into contact with the inturned end of spring 5. This arrested action results in the arm 3 being swung from the latch 14 outwardly and against the tension of spring 11, said spring 5 being tensioned sufficiently 20 to overcome the latch and coiled spring. When the arm has reached its outward limit of movement, the spring 5 then yields to permit the pin 21 to ride thereby and out of the channel down onto the record groove 25 at its beginning. The shuttle and its arm being now released, coiled spring 11 acts to return the same to normal position where it is retained by the latch 14.

The attachment or device is designed for 30 use with varying sized records and for this reason the disk 12 is rotatably mounted on the pivot pin 2 beneath the arm 3 and carries an upstanding stop 24 with which the arm 3 is adapted to engage at its outward 35 limit of movement. When the stop has been properly adjusted, the disk is held fixed by means of an overlying clamp arm 25 and the thumb screw 26 threaded into the base 1.

The base is formed with a central aperture 27 to receive the center post 28 common 40 to all disk tables 29. It will therefore, be obvious that in order to change from one record to another, the base 1, with its supported superstructure, is quickly removed 45 in a manner similar to the removal of the disk and is likewise replaced following the placing of the record on its table. The attachment is readily attached to present makes of talking machines with any modification thereof whatever unless possibly in 50 the provision of screw holes in the sound box for the screws 16 in makes that do not have a removable back plate embodied in the sound box construction. The transfer 55 of the sound box outwardly occurs within approximately one quarter revolution of the turntable and during which the stylus is carried low and in proximity to the disk record whereby when the stylus is replaced 60 on the record the action will be gentle and without jar or injury to either the record or stylus. When the repeat attachment is 65 not being used the central portion may be removed and stored away while the part carried by the sound box will not interfere with

the usual operation of playing or reproducing a record.

Having thus described my invention, what I claim as new and desire to secure by Letters Patent is:—

70 1. In a repeat device for phonographs, an actuating member, a shuttle carrying member operatively related to the first member, a shuttle carried by said second member, latching means for the second member, and means whereby the latching means is released upon the stylus engaging the shuttle. 75

2. In a repeat device for phonographs, an actuating member, a shuttle carrying member operatively related to the first member, 80 a shuttle carried by said second member, an obstruction borne by the second member, means to releasably hold the second member against movement, and a part movable with the stylus and engageable with the obstruction to effect release of the said means and to then pass the obstruction and be disengaged therefrom. 85

3. In a repeat device for phonographs, an actuating member, a shuttle carrying member operatively related to the first member, 90 and having a channel, a shuttle carried by said second member, a spring secured at one end and having its opposite end free and extending through an opening provided there- 95 for in the second member and across the channel, a latch for the second member and a part movable with the stylus and against the free end of the spring to effect release of the latch. 100

4. In a repeat device for phonographs, an actuating member, an arm pivoted at one end to the member and having a curved channelled shuttle on its opposite end, a latch for the arm carried by the member, a yieldable element in the channel, and a member movable with the stylus and engageable with the yieldable element to effect release of the latch. 105

5. In a repeat device for phonographs, an actuating member, an arm pivoted at one end to the member and having a curved channelled shuttle on its opposite end, a latch for the arm carried by the member, a spring secured to the shuttle, and having a 110 free end extending across the channel, and a member movable with the stylus and engageable with said free end of the spring to effect release of the latch and to then move past said spring end. 115

6. In a repeat device for phonographs, an actuating member, an arm pivoted at one end to the member and having a curved channelled shuttle on its opposite end, a latch for the arm carried by the member, an ob- 120 struction in the channel and a member movable with the stylus and engageable with the obstruction to effect release of the latch. 125

7. In a repeat device for phonographs, an actuating member, a member connected 130

thereto and having a shuttle extending transversely thereto, said shuttle having a curved track, arranged so that the second member is radial thereto, a member movable with 5 the stylus and on the track and entering one end of the shuttle from one side of the second member and then passing through the opposite end thereof, on the opposite side of the second member and means to effect operation of the parts to replace the stylus on 10

the record during the movement of said stylus member on the track.

In testimony whereof I have signed my name to this specification in the presence of two subscribing witnesses.

FREDERICK A. SHAW.
